BUILDING ELEMENT

Norman P. Harshberger, Scarsdale, N. Y., assignor to Bakelite Building Products Co. Inc., New York, N. Y., a corporation of Delaware

Original application September 20, 1930, Serial No. 483,310. Divided and this application October 10, 1932, Serial No. 636,972

3 Claims. (Cl. 108—7)

This invention relates to improvements in building elements, and is a division of copending application Serial No. 483,310, filed September 20, 1930.

5 In the copending application above referred to, there is disclosed an apparatus for and method of applying coloring to building material to produce relatively large units having lines of demarcation thereon, the units being adapted to 10 operate with one another on the roof in a novel manner to simulate a plurality of relatively small figures, and more particularly, to simulate a brick siding effect. The present application relates more particularly to the shingle unit itself.

15 It is one of the objects of the present invention to provide a shingle unit of relatively large size having a plurality of lines of demarcation delineated thereon, in which the unit is so shaped that it can be cut in an economical manner and so 20 shaped that it will cooperate with other similar units to simulate a plurality of small sized figures, and at the same time cover the roof in an effective and economical manner. A more specific object of the invention is to provide building elements having opposite ends cut in stepped formation, the said stepped edges bearing a definite 25 relationship with lines of demarcation on the elements.

A still more specific object of the invention is to 30 provide building elements having a novel form of locking means for causing proper cooperation of the units with one another on a roof and for holding down portions of the elements to prevent curling and the like.

35 With the above and other objects in view, the invention consists of the improved building elements and all parts and combinations thereof as set forth in the claims, and all equivalents.

In the accompanying drawing illustrating one 40 complete embodiment of the preferred form of the invention in which the same reference numerals designate the same parts in all of the views:

Fig. 1 is a fragmentary plan view of a stencil belt showing the manner of applying coloring material or the like to an elongated web in the manner fully set forth and described in copending application Serial No. 483,310;

45 Fig. 2 is a plan view of a portion of the cutting roller used to produce the building elements forming the subject matter of this invention;

Fig. 3 is a plan view showing the improved element; and

50 Fig. 4 is a plan view showing an assembly of a plurality of said elements.

To produce the improved elements, an elongated sheet of roofing material, which usually comprises a fabric base coated with bituminous material and with a layer of granulated mineral, is fed beneath the stencil belt 16 in the manner fully set forth in copending application above referred to, and coloring material is applied by suitable means to the stencil, said coloring material passing through apertures 29 of the stencil belt and adhering to the web below to create the design 10 thereon.

Inasmuch as the apertures 29 of the stencil belt must be separated at intervals, as at 30, so that portions of the belt will not fall away, the lines of demarcation which will be applied to the web, 15 will be broken at intervals. For this reason, copending application before referred to discloses the use of a printer arranged to apply coloring material to the short sections of the web which are below the portions 30 of the stencil belt. The 20 web will therefore leave the printing roller with continuous lines of demarcation 31 thereon. Next, the web is severed longitudinally and transversely by knives 23 of a cutting roller 22, as fully set forth in copending application to produce 25 from each side of the web a plurality of figured elements such as are illustrated in Fig. 3. Fig. 2 shows a partial development of the cutting roll and knives in which the upper and lower horizontal lines of the figure represent the end edges 30 of the cutting roll.

Each of said elements is then cut inwardly from its lower edge, as at 32, to form a slit for engagement with a lug 33 of an adjacent element. The shingles produced may be laid as shown in Fig. 35 4 with adjacent elements in the same course having overlapping ends which are interlocked through the medium of the lugs and slits 33 and 32, the lower edge of one course of elements overlapping the upper edge of a course below as shown in Fig. 4 to create an effect of a plurality of brick-like figures.

It is to be noted that the step-like end edges of the individual elements cooperate with the lines of demarcation to produce very definite effects, 45 and that said step-like edges make it possible for the elements to be cut out from an elongated web without waste. It is to be noted that the lugs 33 in cutting, form spaces 34 at the other end of each element, but that said spaces appear on ends 50 of the elements which are overlapped in assembly.

It is to be understood that the lines of demarcation may be produced in other ways than by the stencil belt illustrated in Fig. 1 and described in copending application, and that said 55

lines may also be produced by means other than by the application of color, that is, they may be produced by any surface effect creating a shadow or contrast, although for the purpose of simulating siding, a very definite mortar-like line is desirable.

The lines of demarcation 31, are arranged at one end edge of each element to cooperate with the stepped formation, and the lines of demarcation preferably terminate short of the other end edge to provide a space 35 which is to be overlapped in assembly, and said lines further terminate short of the upper edge of each element, as at 38, to provide a space which is overlapped at 39, by elements of the course above. The lines, of course, may be continued over the portions which are to be overlapped, but such continuance would serve no function, the main feature of the arrangement being to so position the lines that when there is a definite overlap, there will be a perfect cooperation of the figures of one element with the figures of overlapping elements. The locking tongue 33 and slot 32, it is to be noted, are so positioned as to insure the abovementioned proper cooperation of the figures.

While the elements have been described as formed from the usual composition material having a flexible base, they may be formed as rigid units wherein the base is composed of rigid material, such as a mixture of cement and asbestos, or the like. If built from rigid material, the elements would have the lines of demarcation delineated thereon in any suitable manner to carry out the features of the invention. By the use of rigid material, it would be possible to manufacture a very attractive form of siding having the necessary durability and fire-proof qualities, and at the same time simulating bricks, at an expense much less than the expense ordinarily incurred in laying a brick siding.

Other changes and modifications may be made without departing from the spirit of the invention, and all of such changes are contemplated as may come within the scope of the claims.

45 What I claim is:

1. A building element comprising a base strip, a wear resistant surfacing layer extending over the base strip on the face of the element to be exposed when laid, and a design formed on said

surfacing layer simulating the spaces between and surrounding a plurality of completed configurations, said design comprising an adhered layer of coloring material of contrasting visual effect with the configurations, a portion of the design located between the ends of a configuration and extending without the configurations whereby to provide marker means for the vertical and horizontal positioning of overlapping elements in assembly to create a continuous area of staggered simulated configurations. 5

2. A brick and mortar simulating element and the like comprising a base strip, a surfacing layer extending over the base strip on the face of the element to be exposed when laid, and a design 15 formed on said surfacing layer simulating mortar joining a plurality of brick-like figures, said design comprising an adhered layer of coloring material of contrasting visual effect with the brick-like figures, a portion of the mortar design being 20 located between the ends of a brick-like figure and extending vertically without the brick-like figures and adapted in assembly to provide a marker for the alignment with said brick-like figures of edges of an overlapping strip of an 25 adjacent course of elements to create a continuous area of staggered simulated brick-like figures separated by mortar joints. 30

3. A building element comprising a base strip, 30 a surfacing layer extending over the base strip, and a design formed on the lower portion of said strip on said surfacing layer simulating the vertically and horizontally disposed mortar lines between and surrounding a plurality of brick-like figures, said design comprising an adhered layer 35 of coloring material of contrasting visual effect with brick-like figures, certain mortar lines cooperating with edges of the element and others providing vertical extensions thereof into the upper portion of the strip above the completed figures and having a depth substantially the depth of a brick configuration, said extensions providing definite positioning means for the edges of overlapping elements of an overlying course 40 whereby to complete other brick-like figures 45 separated by mortar lines and to form a continuous area thereof. 40
